UNITED STATES PATENT OFFICE.

RENO J. BUSH, OF BLOOMSBURG, PENNSYLVANIA.

DISPENSING CONTAINER.

1,405,753.

Specification of Letters Patent. Patented Feb. 7, 1922.

Application filed April 1, 1920. Serial No. 370,613.

To all whom it may concern:

Be it known that I, RENO J. BUSH, a citizen of the United States, residing at Bloomsburg, in the county of Columbia and State of Pennsylvania, have invented certain new and useful Improvements in Dispensing Containers, of which the following is a specification.

This invention relates to a dispensing container for serving salted nuts, such as peanuts, almonds and the like.

The invention has, as one of its objects, the provision of a dispensing container which will serve nuts and the like in exactly measured quantities for each operation of the device.

Another object of the invention is the provision of a device of this character which is so constructed that the quantity to be dispensed may be varied.

The invention has as a still further feature the provision of means for removing and collecting surplus salt carried by the nuts.

Still another feature of the invention resides in the manner of joining the separate sections of the container together, whereby the sections are easily separated from one another for purposes of cleansing.

In the drawings:

30 Figure 1 is a front elevation of a dispensing container constructed in accordance with the present invention;

Fig. 2 is a section on the line 2—2 of Fig. 1;

35 Fig. 3 is a side elevation of a modified form of the container;

Fig. 4 is a vertical transverse section of the dispensing spout;

40 Fig. 5 is a vertical longitudinal section of the dispensing spout;

Fig. 6 is a top plan view of one of the members used in forming the joint between the parts of the device;

45 Fig. 7 is a vertical section through the joint between two of the parts.

In detail:

The invention, as herein shown, comprises a glass jar 1 having an opening at the top thereof closed by a suitable cover 2 and an opening at the bottom as indicated at 3. The rim of the opening 3 is provided with flanges of segment form as shown at A in Fig. 6 for purposes to be hereinafter described. An intermediate section 4 and a base section 5 are similarly provided with

such flanges on their peripheral edges as indicated at 6 and 7 respectively.

The base 5 receives a ring 8 formed with a segmental flange 9 cooperating with the flanges 7 on the base 5 to hold the said ring 60 8 thereto. The ring 8 is provided with a wall 10 whereby the ring forms a receptacle for surplus salt as will be hereinafter described. Associated with the ring 8 and received by flanges 11 thereof are the flanges 6 of the intermediate member 4 which consists of a glass body 12 having the sloping perforate wall 13 which ends in a spout 15. The intermediate body 4 carries a metal ring 16 which has flanges 17 cooperating with the flanges on the opening 3 of the glass jar 1 and it is by means of the said flanges on the respective parts that the same are held in their assembled relation but may be easily removed by rotation relative to each other 70 75 for cleansing. The end of the spout 15 may be formed with threads or any other suitable means for securing thereto a dispensing spout 18 which comprises a body 19 of substantially cylindrical form but open at the 80 ends and having a nipple 20 threaded for connection with the spout 15; an outlet nipple 21 is also provided. Disposed within the cylindrical body 19 is a cylindrical element 22 having openings 23 and 24 85 which may be brought into registration with the end of the spout 15 or the opening of the nipple 21 at different times but never at the same time with both openings. This cylindrical member 22 is threaded on each end to receive the end closures 24' which also form 90 a bearing at 25 on the cylindrical member 19. Through the bosses 26 on the members 24 is fitted a spindle 27 which carries the disk-like members 28 having bosses 29 provided 95 with screws 30 by means of which the said disk like members 28 may be secured to the spindle 27 at different points therealong in order to provide for varying the available capacity of the cylindrical member 22. A 100 U-shaped handle member 31 is provided with members 32 keyed as at 33 to the bosses 26 of the ends 24'; said U-shaped handle member is provided with an extension 34 carrying a knob 35. The handle member 31 and 105 the disk 24' and cylindrical member 22 are assembled with respect to each other in such manner that when the handle member stands in the position shown in Fig. 5 the opening 24 in the cylindrical member 22 will register 110

with the end of the spout 15 while the opening 23 will be out of registration with the nipple 21 and therefore the cylindrical member 22 between the disks 28 will be filled with 5 whatever is contained in the glass jar 1. However, on rotating the handle member 31 to the position shown in Fig. 2 the result will be that the opening 24 will be displaced out of registration with the spout 15 and the 10 opening 23 will be brought into registration with the nipple 21 thereby delivering a measured quantity of the commodity which is in the receptacle 1. This construction is particularly advantageous in dispensing 15 nuts and the like at soda fountains for use on ice cream but may be equally well used in grocery stores, the capacity of the cylindrical container 22 with the disks 28 set at certain locations being definitely known, as 20 for instance if the disks are set so as to receive exactly one pound of some commodity such as sugar or the like within the container 22 then a clerk selling five pounds of such commodity would only have to operate the 25 handle member 31 five times to know that he had dispensed five pounds of sugar, thereby making it unnecessary to weigh the amount.

In Fig. 3 there is shown a modification 30 of the base for the container. In this construction the base comprises a vertical arm 36 having the jaw members 37 and 38, the latter of which is provided with a thumb screw 39 for clamping the bracket to a 35 table. A ring like extension 40 is carried by the arm 36 and provided with an opening having flanges spaced as indicated at A in Fig. 6. The bottom portion of the device shown in Fig. 3 may be of glass and form a 40 receptacle 41 with a perforate partition 42 and a spout 43 while the upper portion is a glass jar 44 identical with the one shown in connection with Figs. 1 and 2 and the dispensing means 45 is identical with that previously described.

The construction herein shown is illustrated merely as a specific embodiment of a practical form of the invention but in commercializing the same it is to be understood that 50 various departures from the specific construction herein shown may be resorted to without departing from the spirit of the claims.

I claim:

55 1. A dispensing container for commodities coated with a granular substance comprising a reservoir, a conveyor leading from the reservoir to a point of delivery, means for controlling discharge at the point of delivery, 60 and means for separating excess granular substance from the commodities as they pass to the point of delivery.

2. A dispensing container comprising a reservoir, a base having a discharge spout 65 with a perforate bottom wall, said spout

being in communication with the interior of said reservoir, and a receptacle beneath the bottom wall of said spout and within said base for receiving granular matter.

3. A dispensing container comprising a 70 reservoir, a base having a discharge spout with a perforate bottom wall, said spout being in communication with the interior of said reservoir, a receptacle within the base for receiving granular matter, and means 75 carried by said spout for dispensing measured quantities.

4. A dispensing container comprising a reservoir, a base having a discharge spout with a perforate bottom wall, said spout 80 being in communication with the interior of said reservoir, a receptacle included within the base for receiving granular matter, and means carried by said spout for dispensing measured quantities and including mechanism for varying the capacity of said means.

5. A dispensing container comprising a reservoir, a base having a discharge spout with a perforate bottom wall, said spout being in communication with the interior of 90 said reservoir, a cylindrical end carried by said spout and having a nozzle out of alignment with the spout body, and a movable container within said cylindrical end and having openings one registering with the 95 spout in one position of said container and the other registering with the nozzle for discharge in the other position of said container, said base providing a receptacle for receiving granular matter.

100 6. A dispensing container comprising a reservoir, a base having a discharge spout with a perforate bottom wall, said spout being in communication with the interior of said reservoir, a cylindrical end carried by 105 said spout and having a nozzle out of alignment with the said spout body, a movable container within said cylindrical end and having openings one registering with the spout in one position of the container and 110 the other registering with the nozzle for discharge in the other position of said container, means included within said container for varying the capacity thereof, and a receptacle included within the base and co-operating with said perforate bottom wall whereby granular matter is received in the 115 said receptacle.

7. A dispensing container comprising a reservoir, a conveying spout leading from 120 the reservoir and provided with a cylindrical end, a discharge spout depending from said cylindrical end, a cylindrical member within said end and concentric therewith and having openings in its circumferential wall, 125 disk-like members movable toward or from each other axially of said cylindrical member at opposite sides of the conveying spout to vary the capacity of said cylindrical member, means closing the ends of said cylindri- 130

cal member and forming stops for said disk-like members, and means for rocking the cylindrical member whereby it may receive material through one of said openings from the conveying spout and subsequently discharge the material through the other opening and the discharge spout.

8. A dispensing container comprising a reservoir, a conveying spout leading from the reservoir and provided with a transverse cylindrical end, a delivery spout depending therefrom, a closed cylinder rotatable within said cylindrical end and having peripheral openings, a rod extending axially through

said cylinder, disks movable along said rod at opposite sides of the conveying spout to approach or recede from each other for varying the cubical receiving area of said cylinder, and a handle member secured to said rod and to the cylinder and normally extending over the cylindrical end of the conveying spout and operable to rock the cylinder whereby the openings in the cylinder may be set to receive measured quantities of material from the conveying spout and discharge the same through the delivery spout.

In testimony whereof I affix my signature.

RENO J. BUSH. [L. s.]
